HEADING MACHINE

Lee Berkebil, Detroit, Mich., assignor to B. W. Manufacturing Company, Detroit, Mich., a corporation of Michigan

Original application March 16, 1936, Serial No. 69,242. Divided and this application May 25, 1938, Serial No. 210,010

38 Claims. (Cl. 29—33)

This invention relates generally to heading machines and constitutes a division of my application filed March 16, 1936, bearing Serial No. 69,242.

One of the essential objects of this invention is to provide the stock with an adjustable stop that determines the length of blank to be cut by the shearing mechanism.

Another object is to provide a stop of this type that is adapted, when a length slightly greater than that required for the blank is advanced toward the shearing mechanism, to feed backward the proper distance to provide just the proper length to be sheared.

Other objects, advantages and novel details of construction of this invention will be made more apparent as this description proceeds, especially when considered in connection with the accompanying drawings, wherein:

Figure 1 is a plan view of my improved mechanism as applied to a heading machine;

Figure 2 is a longitudinal section partly in elevation taken substantially on line 2—2 of Figure 1, and showing diagrammatically by dot and dash lines the position of a die for engagement with the stock when the latter is to be drawn through the die;

Figure 3 is a similar view showing the parts in a different position of adjustment;

Figure 4 is a cross section through the straightening means on line 4—4 of Figure 2;

Figure 5 is a cross section through the feeding means on line 5—5 of Figure 2;

Figure 6 is a similar section taken on line 6—6 of Figure 2;

Figures 7 and 8 are end elevations showing the shearing and transferring means;

Figures 9, 10, 11 and 12 are views showing the successive operations of the heading means;

Figures 13 and 14 are diagrams illustrating the operating and timing mechanism.

Referring now to the drawings, A is a bed, B is a horizontal reciprocating member traveling in way C upon said bed and carrying a vertical reciprocating slide B' to which is fastened a punch block B". The member B is reciprocated by suitable mechanism including a rotary crank shaft E and a connecting linkage F between the same and the member B.

G designates the straightening dies, H is a reciprocating feed mechanism, and I is a drawing or sizing die.

As shown, the stock J, preferably hot-rolled, is first delivered to the straightening dies G; is then engaged by the feeding mechanism H; and is lastly passed through the drawing and sizing die I. This specific arrangement is not absolutely essential, but I prefer the same as it avoids any marring, such as might occur if the feed

mechanism were to engage the stock after passing through the die.

The straightening mechanism G may be of any suitable construction adapted to take out any curvature in the stock as delivered thereto. As shown, it consists of a pair of jaws G', G² which are slidably secured in a frame including the side plates G³, G⁴ and spacers G⁵, G⁶. The frame is slidable in ways G⁷ fastened by bolts G¹³ to the bed A. As shown, these ways G⁷ comprise vertically spaced horizontal bars provided in their inner faces at their opposed edges with longitudinally extending slots or channels G¹⁴ that receive vertical ribs G¹⁵ of the side plate G³ of the slidable frame and permit a limited movement thereof. The jaws G' and G² are held from endwise movement by keys G⁸ engaging the plates G³ and G⁴. The lower jaw G² is adjusted vertically by two spaced set screws G⁹ which permit of properly aligning it with the work, and the jaw G' is adjusted by a single set screw G¹⁰. Thus, these jaws can be clamped upon the work with just sufficient pressure to perform the straightening operation and to give the necessary resistance against back feeding. The sliding movement of the frame is limited by stops G¹¹. These are preferably set screws which threadedly engage lugs G¹⁶ of the ways G⁷ in the path of the plate G³ forward and in rear thereof. These stops may be adjusted in the lugs G¹⁶ to prevent the straightener from being carried backward during the rearward movement of the feed mechanism.

The feed mechanism H comprises a pair of plates H' and H² with intermediate spacer members H³ and H⁴, these parts being secured to each other by bolts H⁵. The members H³ and H⁴ have oppositely inclined inner edges, while their outer edges are formed into racks H⁶. Shoes H⁷ secured to the bed by bolts H⁸ engage the upper and lower edges of the inner plate H¹ to form guideways therefor. Within the space between the members H³ and H⁴ are arranged a pair of jaw members H⁹ and H¹⁰ which are wedge-shape and have their outer edges arranged parallel to the inclined inner edges of the members H³ and H⁴. Rollers H¹¹ are arranged between the parallel faces of the jaw members and the members H³ and H⁴, and springs H¹² bearing against the large ends of the wedged jaw members H⁹ and H¹⁰ yieldably press the same in a rearward direction. The whole construction constitutes a frictional one-way clutch which will cause the jaw members H⁹ and H¹⁰ to grip the work when moving in a forward direction and to release it when moving in a rearward direction. This forward and reverse movement is effected by pinions H¹³ which engage the rack members H⁶ and are mounted on shafts H¹⁴ carried by the bed. The plates H' and H² extend respectively above and

below the racks H^8 so that the pinions H^{13} hold the same from lateral movement. The arrangement is such that when motion is imparted to the pinions H^{13} in the direction indicated by the arrows in Figure 2, the jaws will grip the stock and feed it forward, while upon a reverse rotation of the pinions as indicated by the arrows in Figure 3, the stock will be released and the plates and jaws will be moved rearward. The shafts H^{14} are connected to each other by intermeshing gears H^{15} and one of these gears is actuated by mechanism to be hereinafter described.

The sizing die I may be of any suitable construction adapted to slightly reduce the diameter of the stock when pressed therethrough and to impart thereto a finished surface. This die is mounted on the bed in alignment with the straightening dies G and feed mechanism H, and a tank I' adjacent to the die contains a suitable lubricant for reducing friction during the drawing operation and for coating the stock to facilitate the heading operations. There is also an upwardly opening tank G^{12} of sheet metal receiving and forming a jacket for the straightening mechanism G and containing a lubricant for the stock in passing therethrough. Preferably this tank is held in place by the bolts G^{13} used to fasten the ways G^7 to the bed A, and has suitable openings for receiving the stops G^{11} .

Forward of the die I in the direction of feed there is a cut-off mechanism which is associated with other elements of the particular machine to which the cut-off blanks are to be fed. If this machine is, as shown, a heading machine, the stock is cut into suitable lengths and then transferred laterally to a heading die. The specific construction of this heading machine forms no part of the present invention and I shall, therefore, only describe it generally. Mounted on the bed is a member J' apertured for the passage of the stock therethrough and forming one member of a shear. The cooperating member J^2 of the shear is mounted to slide transversely across the face of the member J' and in so doing to sever the projecting portion of the stock. The member J^2 has secured thereto a resilient clip J^3 which yieldably holds the cut-off blank during transfer of the same into alignment with the heading die and punch members K, K' and K^2 . These members are adapted to engage the blank after which it will be released by the clip J^3 and the latter together with the member J^2 will be returned to initial position.

It is desirable to provide means for very accurately gaging the length of the cut-off blanks. This might be accomplished by regulating the angle of oscillation of the pinions H^{13} , but it would be difficult to accomplish this with the degree of accuracy required. I, therefore, adjust the angle of oscillation to slightly greater than the length of feed required and subsequently feed the stock backward. This is accomplished by an adjustable stop L which in one position is in alignment with the projecting portion of the stock and during the movement of the head B will bear against the outer end of said projecting portion and feed it backward. The stop L is attached to a block L' which in turn is adjustably mounted on punch block B². In operation block B² is moved vertically from a position where the stop L aligns with the stock to a position out of alignment therewith. The stop L is preferably provided with a screw threaded shank engaging the block L', and a locknut L' serves to hold this shank in each position of adjustment.

The general operation of the mechanism is as follows:

The shaft E has a crank or eccentric E' thereon which is connected by a rod F with the reciprocating member B. The shaft E also has a gear wheel E² which drives an intermeshing gear wheel E³ in a 1 to 2 ratio. The gear wheel E³ is on a shaft E⁴ which extends to the opposite side of the machine and on each end of this shaft is a variable throw crank. On one end the crank O has a slot O' for engaging a crank pin O² which is adjustable radially in said slot to increase or diminish the throw thereof. This pin is connected by a rod O³ with a bell crank lever O⁴ and with a corresponding adjustable crank pin O⁵ on the actuating arm of said lever. The other arm of the lever is connected by a coupling pin O⁶ with one of the gears H¹⁵, the arrangement being such that for two revolutions of the crank shaft E, one revolution is imparted to the crank O' and one reciprocation to the rod O³ and bell crank lever O⁴. Also, when the coupling pin O⁶ is in engagement with the gear H¹⁵, the latter and the shafts H¹⁴ and pinions H¹³ will be oscillated through an arc varying according to the adjustment of the cranks.

On the opposite end of the shaft E⁴ is a variable throw crank P similar to O, the crank pin of which is connected by a rod P' with a slide P². This slide has a cam slot P³ which engages a pin P⁴ on the shank of the shear member J². Thus, each two revolutions of the crank shaft E will effect one reciprocation of the shear J², and the slot P³ is suitably fashioned to give the desired timing of this movement.

At an intermediate point on the shaft E⁴ is mounted a cam Q which actuates a reciprocating member Q' connected to a rock arm Q² on a rock shaft Q³ which has an arm Q⁴ for actuating the slide B'. The cam Q is so fashioned as to intermittently raise and lower the slide B' with a dwell at each end of the movement thereof.

With the mechanism as described, it will be understood that two reciprocations are imparted to the slide B to each reciprocation of the shear J² and of the slide B'. Also, that while the shear J² is stationary in the position shown in Figure 1, the stock is advanced by the feed mechanism a length slightly greater than that required for the blank and is then fed backward by the gage stop L which impinges thereagainst. This will exactly determine the length to be cut off after which the shear J² is actuated to effect the cut-off and to transfer the blank into alignment with the punch and dies.

In the complete operation, each forward movement of the feed mechanism H will first grip the stock between the jaws H⁹ and H¹⁰ and then move it forward an amount determined by the adjustment of the cranks O' and O⁵. During this movement, the stock is drawn through the jaws of the straightening dies G' and G², and it is also pressed forward through the sizing die I which latter is formed of exceedingly hard material, such as tungsten carbide. After the completion of the forward movement and during the rearward movement of the feeder H, the stop L which is in alignment with the projecting portion of the stock will contact therewith and effect a slight rearward movement. This is permitted by the sliding of the frame of the straightening dies G' and G², while the die I will offer sufficient frictional resistance so as to prevent any overfeeding in this reverse direction. It will thus be appreciated that during each cycle, hot-

rolled stock, preferably delivered from a coil, is fed forward being first straightened and subsequently delivered to the sizing die I through which it passes, and thence through the member J' to project outward beyond the same. The projecting portion is then pressed rearward by the stop L and subsequently sheared off and delivered to the heading die.

If, at any time, there should be necessity for stopping the feeding of the stock, this may be quickly accomplished by withdrawing the pin O⁶ which will disengage the bell crank O⁴ from the gear wheel H¹⁵ and will, therefore, stop the oscillation of the gear pinions H¹³. If desired, a sizing die such as X designated diagrammatically by dot and dash lines in Figure 2 may be rigidly mounted upon the bed A between the straightening mechanism G and the feed mechanism H. In this instance the stock J would be drawn by the feeding mechanism H through the sizing die X after passing through the straightening mechanism G. When such a sizing die X is located as desired, the sizing die I may be used as an additional die or dispensed with entirely, as desired. Otherwise, the structure would be the same as that previously described.

What I claim as my invention is:

1. In mechanism of the class described, a sizing die, a heading die, means for advancing stock through said sizing die toward said heading die, means intermediate said dies for cutting said stock into blanks, and means independent of the advancing means carried by said heading die and operable when a length greater than that required for a blank is advanced toward said cutting means to feed backward the stock the proper distance to provide the proper length to be cut.

2. In mechanism of the class described, a reciprocating heading die, a die for sizing stock before it reaches the heading die, reciprocating means for moving stock through said sizing die, and a gage stock stop for the stock carried by said heading die.

3. In mechanism of the class described, a sizing die, a heading die, means for moving stock through said sizing die toward said heading die a length slightly greater than that required for a blank, and a gage stop for the stock operable independently of the stock moving means to feed the stock backward the proper amount to provide exactly the proper length of blank to be cut off.

4. The combination with a bed, of a reciprocating header thereon, a reciprocating stock feeder including a one-way clutch for engaging the stock, shearing means intermediate said feeder and header, and a gage stop carried by said header for impinging against the end of the stock to slightly back feed the same and to obtain an exactly measured sheared length.

5. The combination with a bed, of a reciprocating header thereon, a reciprocating stock feeder including a one-way clutch for engaging the stock, means for varying the amplitude of reciprocation of said feeder, and an adjustable gage stop on said header for impinging against the end of the stock to slightly back feed the same and to obtain an exactly measured sheared length.

6. The combination with a bed, of a reciprocating header mounted thereon, a reciprocating stock feeding means also mounted on said bed in advance of said header and including a one-way clutch for engaging the stock, shearing means intermediate said feeding means and header, a sizing and finishing die intermediate said shearing

means and feeding means through which the stock is pushed by the latter, and a gage stop carried by said reciprocating header for impinging against the end of the stock to slightly back feed the same and to obtain an exactly measured sheared length.

7. The combination with a bed, of a reciprocating header mounted thereon, a reciprocating feeding means also mounted on said bed in advance of said header, timed driving mechanism for said reciprocating header and said reciprocating feeding means through which there occurs a plurality of reciprocations of the former to one of the latter, shearing means intermediate said feeding means and header, a gage stop carried by said header, and means for registering said gage stop with the end of the stock during one of the reciprocations of said header to slightly back feed the stock and to obtain an exactly measured sheared length.

8. In mechanism of the class described, a reciprocating heading die, a die for sizing the stock before it reaches the heading die, reciprocating means for feeding stock to said sizing die, means intermediate the sizing and heading dies for shearing the stock, a gage stop carried by the heading die, and means for registering said gage stop and with an end of the stock to slightly back feed the stock and to obtain an exactly measured sheared length.

9. In mechanism of the class described, a reciprocating heading die, a die for sizing the stock before it reaches the heading die, reciprocating means for feeding stock to said sizing die, means intermediate the sizing and heading dies for shearing the stock, and an adjustable gage stop carried by said heading die for impinging against an end of the stock to slightly back feed the same and to obtain an exactly measured sheared length.

10. The combination with a bed, of a reciprocating header mounted thereon, a reciprocating stock feeding means in advance of said header and including a one-way clutch for engaging the stock, shearing means for the stock in advance of the header, a sizing and finishing die intermediate said feeding means and header, and a gage stop carried by said reciprocating header for impinging against an end of the stock to slightly back feed the same and to obtain an exactly measured sheared length.

11. The combination with a bed, of a reciprocating header mounted thereon, a reciprocating feeding means in advance of said header, timed driving mechanism for said reciprocating header and said reciprocating feeding means through which there occurs a plurality of reciprocations of the former to one of the latter, shearing means for the stock in advance of the header, a gage stop carried by said header, and means for registering said gage stop with an end of the stock during one of the reciprocations of the header to slightly back feed the stock and to obtain an exactly measured sheared length.

12. In mechanism of the class described, a reciprocating heading die, a die for sizing stock before it reaches the heading die, reciprocating means for feeding stock to said sizing die, means intermediate the sizing and heading dies for shearing the stock, and a gage stock stop for the stock carried by said heading die.

13. The combination with a bed, of a reciprocating header thereon, a shear for the stock adjacent said header, a reciprocating feeder for advancing the stock toward the shear, and an ad-

justable gage stop carried by said header independent of the feeder for impinging against an end of the stock advanced by the feeder to slightly back-feed the same to obtain a predetermined length to be sheared.

14. The combination with a bed, of a reciprocating header die, a die for sizing stock before it reaches the heading die, means for advancing stock through the sizing die toward the heading die, means intermediate the sizing and heading dies for shearing the sized stock, and a gage stop for the sized stock carried by the heading die and operable independently of the advancing means to slightly back-feed the stock to obtain an exactly predetermined length of sized stock to be sheared.

15. In a machine of the class described, the combination with a horizontally slidable head, and a vertically slidable punch block carried by said head, of means for advancing stock toward said punch block, means intermediate the advancing means and punch block for shearing the stock, the advancing means being operable to advance the stock an amount greater than the length of blank to be sheared, and means carried by the vertically movable punch block and operable independently of the stock advancing means to feed the stock backward the proper amount to provide exactly the desired length of blank to be sheared.

16. In a machine of the class described, the combination with a horizontally slidable head, and a vertically slidable punch block carried by said head, of means for advancing stock toward said punch block, means intermediate the advancing means and punch block for shearing the stock, the advancing means being operable to advance the stock an amount greater than the length of blank to be sheared, and a stop adjustably mounted on the vertically movable punch block and operable independently of the stock advancing means to feed the stock backward the proper amount to provide exactly the desired length of blank to be sheared.

17. In a machine of the class described, a sizing die, a punch block in advance of said die, means for moving stock through said die toward said punch block, means intermediate the moving means and punch block for shearing the sized stock, the moving means being operable to advance the stock an amount greater than the length of blank to be sheared, and means carried by the punch block and operable independently of the stock moving means to move the stock backward the proper amount to provide exactly the desired length of blank to be sheared.

18. In a machine of the class described, a sizing die, a punch block in advance of said die, means for moving stock through said die toward said punch block, means intermediate the moving means and punch block for shearing the sized stock, the moving means being operable to advance the stock an amount greater than the length of blank to be sheared, and a stop adjustably mounted on the punch block and operable independently of the stock moving means to move the stock backward the proper amount to provide exactly the desired length of blank to be sheared.

19. In a machine of the class described, the combination with a vertically movable punch block, of a one-way clutch movable forwardly and rearwardly relative to said punch block, said clutch being operable to grip the stock and move it forwardly toward the punch block and oper-

able to release the stock when moving in a rearward direction, means for straightening the stock before it reaches said clutch, said straightening means being mounted for a limited sliding movement in line with the movement of the stock, said straightening means providing just sufficient pressure to perform the straightening operation and to offer resistance to rearward movement of the stock, means intermediate the clutch and

10 punch block for shearing the stock, the clutch being operable to advance the stock an amount greater than the length of blank to be sheared, and means carried by the punch block and operable independently of the clutch to backfeed the stock to provide exactly the desired length of blank to be sheared.

20. In a machine of the class described, the combination with a vertically movable punch block, of a one-way clutch movable forwardly and rearwardly relative to said punch block, said clutch being operable to grip the stock and move it forwardly toward the punch block and operable to release the stock when moving in a rearward direction, means for straightening the stock before it reaches said clutch, said straightening means being mounted for a limited sliding movement in line with the movement of the stock, said straightening means providing just sufficient pressure to perform the straightening operation and to offer resistance to rearward movement of the stock, means intermediate the clutch and punch block for shearing the stock, the clutch being operable to advance the stock an amount greater than the length of blank to be sheared, 25 and an adjustable stop carried by the punch block and operable independently of the clutch to backfeed the stock to provide exactly the desired length of blank to be sheared.

21. In a machine of the class described, the combination with a horizontally slidable head, and a vertically slidable punch block carried by said head, of means for advancing stock toward said punch block, means intermediate the advancing means and punch block for shearing the stock, the advancing means being operable to advance the stock an amount greater than the length of blank to be sheared, a stop adjustably mounted on the vertically movable punch block and operable independently of the stock advancing means to feed the stock backward the proper amount to provide exactly the desired length of blank to be sheared, and means carried by a part of the shearing means for holding the cut-off blank during transfer of the same into alignment 30 with the punch block.

22. In mechanism of the class described, a sizing die, means for moving stock through said die a length slightly greater than that required for a blank, and a gage stop for the stock operable to feed the stock backward the proper amount to provide exactly the proper length of blank to be cut off.

23. In a machine of the class described, a sizing die, means in advance of said die for shearing the sized stock, means for moving stock through the die past said shearing means, and means in advance of said shearing means operable independently of said stock moving means to move the stock backward relative to said shearing means the proper amount to provide the desired length to be sheared.

24. In mechanism of the class described, a sizing die, means for moving stock through said die a length slightly greater than that required for a blank, means in advance of the die for shear-

ing the sized stock, and a gage stop for the stock in advance of the shearing means operable to feed the stock backward the proper amount to provide the desired length of blank to be sheared.

25. In a machine of the class described, a sizing die for stock, means in advance of the sizing die for shearing the sized stock, means for advancing stock through the die past the shearing means to provide a blank to be sheared, and means in advance of the shearing means for moving the stock backward the proper amount to provide the desired length of blank to be sheared, said backward moving means being free and operable independently of the stock advancing means, the die being immovable during advancement of the stock and frictionally resisting backward movement of the stock.

26. In a machine of the class described, a sizing die for stock, means in advance of the sizing die for shearing the sized stock, means for advancing stock through the die past the shearing means to provide a blank to be sheared, and means in advance of the shearing means for moving the stock backward the proper amount to provide the desired length of blank to be sheared, said backward moving means being free and operable independently of the stock advancing means and including an adjustable member in the path of the sized stock.

27. In a machine of the class described, means for shearing stock, means for advancing stock past the shearing means to provide a blank to be sheared, and means in advance of the shearing means for moving the stock backward the proper amount to provide the desired length of blank to be sheared, said backward moving means being free and operable independently of the stock advancing means and including a member in the path of the sized stock.

28. In a machine of the class described, a sizing die for stock, means in advance of the sizing die for shearing the sized stock, means for advancing stock through the die past the shearing means to provide a blank to be sheared, and means independent of the stock advancing means in advance of the shearing means for moving the stock backward the proper amount to provide the desired length of blank to be sheared.

29. In a machine of the class described, a sizing die for stock, means in advance of the sizing die for shearing the sized stock, means for advancing stock through the die past the shearing means to provide a blank to be sheared, and means in advance of the shearing means for moving the stock backward the proper amount to provide the desired length of blank to be sheared, said backward moving means including an adjustable member in the path of the sized stock.

30. In a machine of the class described, the combination with a multiple punch block, of means for advancing stock toward said punch block, means intermediate the advancing means and punch block for shearing the stock, the advancing means being operable to advance the stock an amount greater than the length of blank to be sheared, and means independent of the stock advancing means carried by the punch block and operable to feed the stock backward the proper amount to provide exactly the desired length of blank to be sheared.

31. In a machine of the class described, a punch block, means for advancing stock toward

the punch block, means between the advancing means and punch block for shearing the stock, and means carried by the punch block and engageable with the stock to move it backward relative to the shearing means the proper amount to provide the desired length to be sheared.

32. In a machine of the class described, a punch block, means for advancing stock toward the punch block, a stop for the stock adjustably mounted on the punch block, and means between the advancing means and punch block for shearing the stock after it has been engaged by said stop.

33. In a machine of the class described, a shear, means in rear of the shear for advancing stock past the shear, a punch block in advance of the shear movable substantially horizontally toward and from the shear, and a stop for the stock carried by the punch block, said stop being operable when the punch block is moved horizontally toward the shear to feed the stock backward relative to the shear to provide the desired length to be sheared.

34. In a machine of the class described, a bed, means for advancing stock along said bed past a given point thereof, a punch block in advance of said point movable substantially horizontally toward and from said point, and a stop for the stock adjustably mounted on the punch block, said stop being operable when the punch block is moved horizontally toward said point to feed the stock backward relative to said point to provide in advance of said point a predetermined length of said stock.

35. In a machine of the class described, a shear, means in rear of the shear for advancing stock past the shear, a punch block in advance of the shear, and means for moving the stock backward the proper amount to provide the desired length to be sheared, said backward moving means including a member adjustably mounted on the punch block.

36. In a machine of the class described, a shear, means in rear of the shear for advancing stock past the shear, a member in advance of the shear mounted for both horizontal and vertical movements relative thereto, and means carried by said member and operable during horizontal movement thereof to move the stock backward the proper amount relative to the shear to provide the desired length to be sheared.

37. In mechanism of the class described, a shear for stock, means in rear of the shear for moving stock past the shear a length slightly greater than that required for a blank, a punch-block in advance of the shear, and means carried by the punch block operable independently of the stock moving means for moving the stock backward relative to the shear the proper amount to provide the desired length to be sheared.

38. In mechanism of the class described, a shear for stock, a reciprocating feeder in rear of the shear for advancing the stock past the shear, a punch block in advance of the shear, and a gage stop adjustably mounted on the punch block and operable independently of the feeder for impinging against an end of the stock advanced by the feeder to slightly backfeed the stock to obtain a predetermined length to be sheared.
